UNITED STATES PATENT OFFICE.

RALPH M. WHITMAN, OF NEW BEDFORD, MASSACHUSETTS.

CLASP.

Application filed May 2, 1922. Serial No. 557,867.

To all whom it may concern:

Be it known that I, RALPH M. WHITMAN, a citizen of the United States of America, and resident of New Bedford, in the county 5 of Bristol and State of Massachusetts, have invented new and useful Improvements in Clasps, of which the following is a specification.

This invention relates to clasps and is 10 particularly designed to support stockings, socks and other garments.

Objects of the invention are to provide a clasp of the character described which will present a smooth, unobstructed surface on 15 both the inner and the outer sides so as not to be uncomfortable and so as not to push out the overlying garment or garments in an unsightly manner, which will not tear or distort the material which it grips, to render 20 the opening and closing of the clasp simple and convenient, to construct the clasp of few parts which will not readily break or get out of order and which may be cheaply manufactured and assembled, and in general 25 to simplify and improve devices of the class described.

For the purpose of illustration one concrete embodiment of the invention is shown in the accompanying drawings, in which:

30 Fig. 1 is a side elevation;

Fig. 2 is an end elevation with the jaws open;

Fig. 3 is a view similar to Fig. 2 with the jaws closed;

35 Fig. 4 is a view partly perspective and partly in section on the line 4-4 of Fig. 3; and

Fig. 5 is a plan view of the actuator.

The embodiment of the invention shown 40 for the purpose of illustration comprises a clasp constructed of any suitable material preferably a single flat strip of metal bent upon itself to form loop 6 by which the clasp may be supported and shanks 7 and 8 terminating in opposed jaws 9 and 10. Jaws 9 and 10 preferably have integral members 11 which serve to retain pads 12 thereon. Shanks 7 and 8, through a portion 45 of their length, have bent marginal edges forming integral flanges 13, these flanges 50 forming with the shanks 7 and 8 channels 14 in which the inner and outer flanged portions of a block 15 is adapted to slide.

This actuator block or slide is shown in 55 section in Fig. 4 and in plan in Fig. 2. Extending outwardly from slide 15 in the space

between the opposed faces of flanges 13 on shanks 7 and 8 are arms terminating in knobs or handles 16 which are adapted to be grasped by the fingers of the user of the 60 clasp in moving the jaws 9 and 10 to open and closed positions.

Shank 8 is outwardly bowed or bent at 17 to provide a space for the rolled or bunched end of the material which is 65 grasped by the clasp, such as the top of a stocking. To yieldingly retain the clasp in the closed position shown in Fig. 3, one of the shanks, preferably shank 8, is provided with an inwardly disposed projection or 70 bulge 18 which may be produced by indenting the shank at the desired point. The upper end 8' of shank 8 inclines outwardly from the main portion of the shank to permit the clasp to open more widely when the 75 slide 15 is moved to the upper ends of the shanks.

The disposition of the parts when the clasp is open is indicated in Fig. 2, slide 15 being at the upper limit of its movement. 80 In closing the clasp, the user grasps the projecting knobs or actuators 16 with his fingers and forces the slide downwardly. As the slide moves downwardly the upper and lower flange portions thereof bear upon 85 flanges 13 and draw resilient shanks 7 and 8 toward each other. The downward movement of the slide 15 is continued until projection 18 snaps behind the block and yieldingly holds it in its downward position 90 (Fig. 3).

From Fig. 2 it will be evident that the space between the lower ends of opposed flanges 13 on shanks 7 and 8 indicated by the dotted line *a* is greater than the space 95 between pads 12 on jaws 9 and 10 which is indicated by the dotted line *b*. Hence it will be apparent that when the clasp is closed as in Fig. 3 the resilient shanks 7 and 8 apply and maintain a considerable pressure 100 upon pads 12 whereby the material grasped between the pads is securely held in place and the clasp maintains a firm grip thereon. The material from which the clasp is constructed is preferably of such resiliency that 105 when slide 15 is drawn upwardly to the position shown in Fig. 2 jaws 9 and 10 will spring apart to release the material previously held thereby.

I claim:

1. A clasp having diverging shanks, jaws on the ends of said shanks, guide means

on the opposed faces of said shanks, and means cooperating with said guide means for forcing said jaws together into clamping engagement.

5. 2. A clasp having diverging shanks, jaws on the ends of said shanks, guide means on the opposed faces of said shanks, and a slide movable longitudinally of the clasp between said shanks, said slide acting upon 10 said guide means to draw said jaws together into clamping engagement.

3. A clasp having integral diverging shanks, jaws on the free ends of said shanks, flanges on the opposed faces of said shanks, 15 and means cooperating with said flanges for drawing said jaws together into clamping engagement.

4. A clasp having integral diverging shanks, jaws on the free ends of said shanks, 20 said shanks having their marginal portions bent to form guide flanges, and a slide having portions extending under said guide flanges whereby when said slide is moved toward said jaws, the latter will be drawn 25 together into clamping engagement.

5. A clasp having diverging shanks terminating in gripping jaws, and means including an actuator slide disposed entirely between the planes of the outer faces of said 30 shanks for opening and closing said jaws.

6. A clasp having diverging shanks terminating in gripping jaws, guides on the inner faces of said shanks, and a slide actuator having parts fitting in the guides of both 35 said shanks for opening and closing said jaws.

7. A clasp having diverging shanks terminating in gripping jaws, the marginal portions of said shanks being turned inwardly 40 into parallel relation with the shanks to form guide channels, a slide actuator having parts fitting into the guide channels of both said shanks, and a handle on said actuator extending laterally between said shanks 45 whereby the actuator may be moved to open or close said jaws.

8. A clasp having diverging shanks termi-

nating in gripping jaws, the marginal portions of said shanks being turned inwardly into parallel relation with the shanks to 50 form guide channels, a slide actuator having parts fitting into the guide channels of both said shanks, handles on said actuator extending laterally between said shanks whereby the actuator may be moved to open 55 or close said jaws, and stop means for said actuator.

9. A clasp having diverging shanks terminating in gripping jaws, means including an actuator slide disposed entirely between 60 said shanks for opening and closing said jaws, and a handle on said slide projecting laterally between said shanks whereby said slide may be moved.

10. A clasp having integral shanks terminating in gripping jaws, means including a slide actuator disposed between said shanks for moving said jaws into closed and open positions, one of said shanks having an outward bulge adjacent its jaw to 70 provide space for a rolled or bunched end of the material gripped by the clasp.

11. A clasp comprising a strip of sheet material bent upon itself to form a loop, diverging shanks terminating in gripping 75 jaws, the marginal portions of said shanks being inturned to form guide channels, an actuator slide having parts interfitting with the guide channels of both said shanks whereby movement of said slide longitudinally of said shanks causes said jaws to advance toward or recede from each other for gripping or releasing material therebetween, said slide being disposed between said shanks, stop means for said slide, and an 85 integral bulge in one of said shanks between its jaw and the closed position of said slide whereby space is provided for the rolled over or bunched end of the material gripped by the clasp.

Signed by me at New Bedford, Mass., this 29 day of April, 1922.

RALPH M. WHITMAN.
